UNITED STATES PATENT OFFICE.

EDWARD CAMPBELL, OF WINDSOR, ONTARIO, CANADA, AND GEORGE A. FAIR, OF DETROIT, MICHIGAN.

LACING DEVICE.

1,220,602.

Specification of Letters Patent. Patented Mar. 27, 1917.

Application filed September 8, 1916. Serial No. 118,973.

To all whom it may concern:

Be it known that we, EDWARD CAMPBELL and GEORGE A. FAIR, citizens of the Dominion of Canada and of the United States, respectively, and residents of Windsor, in the county of Essex and Province of Ontario, Canada, and Detroit, in the county of Wayne and State of Michigan, respectively, have invented a new and Improved Lacing Device, of which the following is a specification.

The object of the present invention is to produce a lacing device particularly adapted for lacing shoes, corsets, plackets and the like; and it consists in a slotted garment having opposed lacing elements located along tapes secured to the edges of the garments and alined with one another longitudinally of said edges, together with a preferably elastic key strip or connecting piece that is slidable longitudinally of said slit to successively engage with the opposed lacing elements, whereby the slit is closed. The invention also consists in a key strip of the character stated having finger grips at its ends whereby it may not only be seized to draw it from open to closing position or vice versa, but is also retained in the positions mentioned.

In the drawings, Figure 1 is a plan view of one embodiment of the invention. Fig. 2 is a transverse section corresponding thereto. Fig. 3 is a fragmentary plan view of a modification. Fig. 4 is a fragmentary plan view of another modification on a line corresponding to the line 4—4 of Fig. 1. Fig. 5 is a fragmentary transverse section showing a further modification.

The numeral 1 indicates two narrow tapes which may be sewed or otherwise attached to the opposed edges of the opening in the shoe, corset, skirt or other garment which it is desired to close. In certain instances, however, the tape may be superseded by the edge portion of the garment itself. Attached to the tapes at short intervals are a series of opposed lacing elements each of which includes a thin flat inner clip 3, preferably metal, having a shallow edge rib or flange 4 which extends longitudinally of the edge of the tape and is turned up away from the body of the user; each lacing element also includes a thin outer clip having a flat body portion 5 and a transversely and outwardly bowed longitudinally extending flange 6

spaced from the inner clip and terminating a short distance from the rib 4. The clips of each unit are preferably connected by tongues 8 which are struck from the body of one of the clips (preferably the inner clip) 60 and pass through the tapes and through holes in the other clip and have their ends bent over. Other means of attachment, such, for example, as small rivets, may, of course, be used. The rows of lacing elements on the 65 opposite edges of the shoe or other garment thus form two longitudinal channels, each of which is adapted to receive one of the edge ribs 10 of a rubber connecting piece or key strip which preferably includes the thin web 70 portion 12 that may terminate at each end in a finger grip 13 having a restricted neck 14, the base of the finger grip being preferably of greater width than the out-to-out distance between the ribs 10. 75

In use, one of the tapes being secured to each edge of the opening of the garment, for example, to each edge of the front of the shoe, it is only necessary to bend the upper finger grip 3 out away from the web 12 to 80 allow engagement of the ribs 10 with the lowermost of the corresponding lacing elements, after which the connecting piece or key may be drawn upwardly until the upper finger piece passes out of the slot between 85 the rows of lacing elements. The finger grip then being released, swings up into the plane of the web and is drawn back downwardly by the elasticity of the body portion of the key until its sides seat themselves against the 90 uppermost lacing elements—thus the key is held from movement in either direction by the two finger grips. Because of the elasticity of the web 12, the two lines of lacing elements may bulge or curve somewhat in respect to each other to adapt themselves to the shape of the crown of the instep or other adjacent portion of the body; and, in certain instances the ribs 10 may be made to diverge 95 from one another for similar purposes. 100

In the modification shown in Fig. 3 the web 12 is partly or wholly omitted and the web portions 10 of the key are joined by a lacing cord 15 which may be drawn in or let out to afford initial adjustment. The ends 105 16 of the rubber afford combined finger grips and retaining members, as before.

In Fig. 4 the lacing elements are shown made up from a pair of duplicate continuous thin metal strips 17 having longitudi- 110

nally spaced transversely curved flange members 18 which constitute the lacing elements. This construction is desirable since it allows the parts to be stamped, dispenses with the 5 operations of assembling necessary in the modifications heretofore described, and insures proper alinement of successive lacing elements. Any desired means, such, for example, as that heretofore described, may be 10 used to secure the strips and the tape together. The term "lacing element" employed in some of the claims thus designates either elements formed separately from or integrally with other elements of the same 15 sort; and the term "key strip" refers to strips made in either one or a plurality of parts.

In the modification shown in Fig. 5, the lacing elements are made separate from each 20 other. Relative twisting is however prevented by the use of a continuous thin metal strip 20 which is interposed between the tapes and the portions of the lacing elements on one side thereof. Rivets 21 are shown 25 fastening the parts together. The configuration of the edge of the key strip is of course modified slightly to correspond to the shape of the channels in which it is to slide.

Various other changes in the details may 30 be made without departing from the spirit of our invention, and we do not, therefore, wish to be limited except as indicated by the subjoined claims.

We claim:—

35 1. Means for lacing slitted garments comprising opposed lacing elements disposed in rows along the edges of the slit, each row of said lacing elements forming a longitudinal channel having a restricted entrance open- 95

40 ing on the side adjacent the other row, an elastic key strip slideable longitudinally of the slit, said strip having edge ribs received in and conforming to said channels, whereby the edges of the garment may be drawn 100 together to close the slit, said elastic key strip having a finger grip at each end arranged to co-act with the corresponding end elements of the rows to positively retain the strip in slit-closing position.

50 2. Means for lacing slitted garments comprising a pair of tapes adapted to be secured to the edges of the garment, inner metal strips disposed along the inner faces of the tapes and having out-turned edge ribs, outer 110

55 metal strips disposed along the outer faces of the tapes and having transversely and outwardly bowed flanges the outer edges of which are spaced a short distance from the rib on the corresponding inner metal strip 115

60 to form longitudinal channels, a key strip

having marginal flanges slideable in the channels whereby the tapes may be drawn together, said key strip having means at its ends adapted to co-act with the ends of one of the metal strips to positively retain the 65 key strip in slit closing position, said outer and inner metal strips being secured together by tongues that are struck from the inner strip and pass through the corresponding tapes. 70

3. Means for lacing slitted garments comprising opposed lacing elements disposed in rows along the edges of the slit, each row of said lacing elements forming a longitudinal channel having a restricted entrance opening on the side adjacent the other row, a flexible key strip slideable longitudinally of the slit, said strip having edge ribs received in and conforming to said channels, whereby the edges of the garment may be drawn 80 together to close the slit, said flexible key strip having a finger grip at one end arranged to co-act with the end elements of the rows to retain the strip in slit-closing 85 position. 75

4. Means for lacing slitted garments comprising opposed lacing elements disposed in rows along the edges of the slit, each row of said lacing elements forming a longitudinal channel having a restricted entrance 90 opening on the side adjacent the other row, a key strip slideable longitudinally of the slit, said strip having edge ribs received in and conforming to said channels, whereby the edges of the garment may be drawn 95 together to close the slit, and a continuous flexible metallic element, independent of the key strip, associated with the lacing elements of each row whereby they are held in proper alinement with reference to the 100 adjacent members of the row of which they are a part. 100

5. Means for lacing slitted garments comprising a pair of tapes adapted to be secured to the edge portions of the garment, 105 opposed lacing elements disposed in rows along the edges of the tapes, each row of lacing elements forming a longitudinal channel having a restricted entrance opening on the side adjacent the other row, a key strip slideable longitudinally of the slit, said strip having edge ribs received in and conforming to said channels, and continuous flexible metallic elements attached, respectively, to the lacing elements of the corresponding row, whereby said lacing elements are held in proper relative alinement. 110 115
